MACHINE FOR OPERATING ON SHEET MATERIAL

Carl M. Yoder, Lakewood, Ohio

Application June 25, 1938, Serial No. 215,931

3 Claims. (Cl. 164—60)

This invention relates to a machine for operating on sheet material while the latter is being fed to and through the machine, more particularly to the mounting of the operating elements on each shaft. In machines of this type, the operating elements, such as slitters or shaping rolls, must be adjusted longitudinally of and fixed to the shaft on which they are mounted, so as to register or co-act with a related element on the other shaft. Heretofore, so far as I am aware, such adjustments have been made by means of a micrometer or by a cut and try method, after the slitters or rolls were placed on the shaft, so that much labor and time was required to set the elements in proper position; and when it became necessary to change the settings of these elements, the same adjustment operations were again required.

One object of the invention is to provide an improved machine of this type wherein a plurality of operating elements may be secured together in an assembled relation as a unit and such unit assembled on a shaft of the machine and removed therefrom at will, this arrangement permitting the adjustments to be made by the use of a gage before the elements are placed on their supporting and driving shaft or by the use of spacers having predetermined widths.

Another object of the invention is to provide an improved machine of this type in which provision is made to support a plurality of operating elements in rigid relation on a member which is removably mounted on and in driving connection with a shaft and to permit ready removal of the member, whereby the machine may be changed to meet various conditions in an easy manner and without undue loss of time.

Other objects of the invention will be apparent to those skilled in the art to which my invention relates from the following description taken in connection with the accompanying drawings, wherein

Fig. 1 is a fragmentary side elevation of a machine embodying my invention, parts being in section or broken away.

Fig. 1a is a fragmentary section of the line 1—1a of Fig. 1.

Fig. 2 is a section on the line 2—2 of Fig. 1.

Fig. 3 is a longitudinal section of an assembly carrying a plurality of slitters or cutters.

Fig. 4 is an elevation of an assembly showing a plurality of slitters or cutters.

Fig. 5 is a view showing a modification.

In the drawings, 1 indicates a support on which are mounted spaced standards 2, 3. The standard 2 is shaped to mount suitable anti-friction bearings 4 for one end of a shaft 5 and an adjustable bearing box 6 for the corresponding end of a shaft 7. The standard 3 is shaped to mount spaced bearings 8, 8a, for the other end of the

shaft 5 and spaced bearing boxes 9, 9a, for the other end of the shaft 7, the standard 3 forming a housing 10 for a suitable driving mechanism for driving the shafts 5, 7, connected to and driven by a shaft 11 from a motor (not shown). The standards 2, 3, are provided with guides 12 (see Fig. 1), in which the boxes 6, 9, 9a, may be raised and lowered for a purpose later set forth, as well as to adjust the shaft 7 relative to the shaft 5 to co-actively relate the operating elements on one shaft to those on the other shaft. For this purpose, a screw 13 is rotatably connected at its lower end to each box 6, 9, 9a, and its upper end is threaded through a nut 13a fixedly mounted in a bridge wall 13'. The upper end of each screw 13 is provided with a worm gear 13b in mesh with a worm 13c (each worm and the adjacent worm gear being mounted in a casing 14) fixed to a shaft 15, so that by rotating the shaft, as by means of a hand wheel 20 16, the screws 13 may be simultaneously operated to raise or lower the boxes 6, 9 and 9a, whereby the shaft 7 is raised or lowered. The casings 14 are mounted on bridge walls 13' suitably secured to the standards 2, 3. The standard 2 is adjustably mounted on the support 1, whereby it may be moved in a direction endwise of the shafts 5, 7, away from the standard 3 for a purpose later set forth. For this purpose, the standard 2 is provided with a shoe 2a which engages ways 1a on the support 1. The shoe is provided with a depending lug 2b, having a threaded opening to form a nut for a screw 18. The screw 18 is rotatably mounted at its opposite ends in bearings 19, 19a, provided on the support 1 and held against endwise movement by a collar 20 engaging the outer wall of the bearing 19 and a cap 20a fixed thereto. Rotation of the screw will operate to slide the standard 2 in either direction.

To permit of the adjustment or movement of the standard 2, as above described and to permit of ready assembly of the shaft 15, the latter is made in sections the adjoining ends of which are connected together by slip-over collars 15a each of which is secured to the adjacent sections by set screws 15b.

21 indicates a sleeve slidably fitting each shaft 5, 7, and keyed thereto by a key 22. The inner end of each sleeve 21, when mounted on its shaft, engages an annulus 23 provided on the inner end portion of the adjacent shaft and its outer end is engaged by a nut 24 removably threaded on the opposite end portion of the adjacent shaft and arranged to clamp the sleeve 21 between it and the annulus 23. Each sleeve 21 is provided at its inner end with an outwardly extending annular flange or wall 21a, forming an abutment, and between this wall and a nut 25, threaded on the outer end portion of the sleeve,

I mount a plurality of operating elements 26 spaced from each other by collars 27 and clamp the elements and collars together by the nut 25.

The operating elements, as well as the spacing 5 collars 27 by preference, on each sleeve 21 are keyed thereto, so as to be driven by the adjacent shaft. The elements 26 and spacers 27 are in the form of construction shown for illustrative purposes, slid onto the sleeve at that end opposite to the abutment 21a. I have shown one collar 27 between each element 26 and the adjoining element 26, but in place of one collar I may use two or more thereof; in either event, the collars 27 may be of a predetermined width 10 so that when the collars 27 and operating elements are assembled on a sleeve 21, the operating elements will have a predetermined spaced relation and will thus be in position to co-act with the predetermined spaced elements on the other 15 sleeve when both sleeves are mounted on the shafts 5, 7. Accordingly, the operating elements and spacers may be mounted on each sleeve 21 with the elements spaced in their predetermined operating position before the sleeve is positioned 20 on its shaft. This arrangement permits more than one sleeve 21 for each shaft with operating elements 26 assembled thereon in varying predetermined relations, to be provided ready for use to meet different conditions, so that it only 25 becomes necessary to remove the sleeves 21 from the shafts 5, 7, and insert thereon sleeves 21 having elements set in the desired spaced relation. In this connection it will be noted that the operating elements and spacers, when assembled 30 on a sleeve, are clamped thereto in rigid relation and may be handled as a unitary structure.

To mount the sleeves and elements thereon on the shafts 5, 7, first, the hand wheel 16 is operated to rotate the shaft 15, which in turn 40 through the screws 13 and bearing boxes 6, 9, 9a, will raise the shaft 7 to disengage the operating elements thereon from the operating elements on the shaft 5; next the slip-over collar 45 15a between the standards 2, 3, will be disconnected from one of the adjacent shaft sections; next the standard 2, bearings 4 and box 6 are moved outwardly on the support 1; and then the nuts 24 are removed from the shafts 5, 7, which 50 will leave the latter supported in their bearings, 8, 8a and boxes 9, 9a. Sleeves 21 with elements 26 assembled thereon are then mounted on the shafts and clamped thereto by the nuts 24. The standard 2 is then moved back into its 55 normal position, the sections of the shaft 15 connected and the bearing boxes 6, 9, 9a, lowered to position the elements 26 on the sleeves in co-active relation. To remove the sleeves 21 and substitute others therefor, these operations are repeated.

In Figs. 1 and 3 I have shown sleeves having four slitting elements 26 mounted thereon arranged to slit sheet material A into three strips and trim off the opposite marginal edges thereof, 60 whereas in Fig. 4 I have shown a sleeve 21 having mounted thereon three slitting elements 26a, which in connection with complementary related slitting elements are adapted to slit sheet material into two strips and trim off the opposite 65 marginal edges thereof. Fig. 5 illustrates a modification wherein the operating elements consist of shaping rolls 26x on a sleeve 21x spaced thereon by collars 27x and keyed to the sleeve as already described. The shaping rolls 26x may 70 be employed for shaping sheet metal during feed-

ing thereof. It will be evident that shaping rolls having any desired cross sectional shape may be mounted on sleeves and the latter positioned on the shafts as herein set forth.

It will be understood that the sheet material 5 may be fed to the operating elements in any suitable manner.

To those skilled in the art to which my invention relates many changes in construction and widely differing embodiments and applications of the invention will suggest themselves without departing from the spirit and scope of the invention. My disclosures and the description herein are purely illustrative and not intended to be in any sense limiting. 15

What I claim is:

1. In a machine of the class described, the combination with a support, of spaced standards mounted on said support, upper and lower shafts rotatably mounted at one end in one of said standards and at their other end rotatably and detachably mounted in the other standard, operating elements on one of said shafts, a sleeve slidably fitting said other shaft and keyed thereto and removable therefrom, operating elements and spacers therebetween on said sleeve, means for securing said elements and spacers together and for securing said elements to said sleeve, separate means for securing said sleeve to the adjacent shaft, that standard on which one end of said shafts are detachably mounted being movable on said support outwardly in a direction longitudinally of said shafts into an inoperative position to disengage the latter to permit removal of said sleeve therefrom, and said other standard serving to support the shafts when said movable standard is moved to its inoperative position, and means for driving said shafts. 30

2. In a machine of the class described, the combination with a support, of fixed and movable standards spacedly mounted on said support, upper and lower shafts rotatably mounted at one end in said fixed standard and at their other end rotatably and detachably mounted in said movable standard, an operating element 45 on one of said shafts, the other shaft being provided with an abutment adjacent said fixedly mounted standard, a sleeve removably and slidably fitting said other shaft and keyed thereto with its inner end engaging said abutment and provided at one end with an annular flange, a nut threaded on the opposite end portion of said sleeve, an operating element and spacers on said sleeve arranged to be secured thereon between said flange and said nut, separate means 50 on the said sleeve carrying shaft and engaging the opposite end of said sleeve for clamping it against said abutment, said movable standard being detachable from said shafts and movable on said support outwardly in a direction longitudinally of said shafts into an inoperative position to disengage the latter to permit removal of said sleeve and said other standard serving to support said shafts when said movable standard is moved to its inoperative position, and 55 means for driving said shafts. 60

3. A machine as claimed in claim 1 wherein is provided means for raising or lowering both ends of the upper shaft simultaneously, said means including a shaft mounted in said standards and comprising a plurality of sections provided with detachable elements to permit the movable standard to be moved on said support. 70
